UNITED STATES PATENT OFFICE

2,304,160

ELEVATOR SIGNAL MACHINE AND SYSTEM

Sampson D. Foster, Cordova, Tenn.

Application July 26, 1939, Serial No. 286,526

13 Claims. (Cl. 177—336)

This invention relates to improvements in elevator signal systems, and particularly to mechanisms, each responsive to movement of an elevator, and circuits therefrom for establishing annunciator signals in the elevators, and related circuits for establishing floor signals indicating the approach and direction of movement of the cars.

It further relates to means and circuits from the elevators thereto, respectively adapted to cut out signal actuation by the mechanisms and thereby neutralize or cancel both the annunciator signals and the floor signals for any particular car.

The mechanism through which circuit control is effected is of that general type which is interconnected with the elevator hoist and which has a head movable in one direction in response and in proportion to the upward movement of the elevator, and in the opposite direction in like response and proportion to the downward movement of the elevator.

The objects of the present invention are:

To provide a simple and efficient mechanism for effecting the establishment and disestablishment of the various circuits.

To provide in such mechanism means through which control operation of the mechanism may be discontinued, and reestablished.

To improve and simplify the design, construction and efficiency of such mechanisms.

To provide circuits connecting the mechanisms respectively each with its related elevator, and means for interconnecting the circuits in series to the elevator annunciator signals, and in parallel to the floor lights.

The means by which the foregoing and other objects are accomplished, and the manner of their accomplishment will readily be understood from the following specification on reference to the accompanying drawings, in which:

Fig. 1 is a plan view of a control machine showing the essential features only thereof, there being one of these machines for each elevator.

Figs. 2 to 7 inclusive are views on substantially double the scale of Fig. 1.

Fig. 2 is a fragmentary sectional elevation taken as on the line II—II of Fig. 1, the position of the traveling carrier head being shifted, however, relatively to that shown in Fig. 1.

Fig. 3 is a transverse sectional elevation taken on the line III—III of Fig. 1.

Fig. 4 is a section of the traveling carrier head taken on the line IV—IV of Fig. 3 and Fig. 1.

Fig. 5 is a section taken on the line V—V of 55

Figs. 3 and 1 showing the bearing for one end of the guide bar, including a detent detail.

Fig. 6 is a section taken as on the line VI—VI of Fig. 1; and

5 Fig. 7 is a substantially identical section showing the guide bar in neutralizing position.

Fig. 8 is a diagrammatic view showing a typical circuit from a group of three control machines to the annunciator signals of the three related elevators and to the hall lights of a typical intermediate floor, the floor here shown as indicated by the annunciator lights being the fourth floor, there being substantially identical circuits for each of the other intermediate floors.

10 The view also shows in light dash lines, the neutralizing control circuit from each elevator to its respective machine, there being only one such circuit for each elevator and machine.

Fig. 9 shows the control circuits from the 20 three machines to their three respective elevators for the top floor annunciator light and hall light; and

Fig. 10 the related circuits for the bottom floor hall lights and annunciator lights.

25 Fig. 11 is a diagrammatic view showing circuits established from a single machine to the related hall lights and an elevator such as is used in department stores where stops are made at all floors and no annunciator is used, there being no interconnection between this circuit and any other circuit. This view also shows the drive from the elevator hoist drum to the control machine, which drive is typical of that used in all the machines.

30 Referring now to the drawings in which the various parts are indicated by numerals:

Each of one or more elevators is provided with a coupled mechanism for controlling the signal lights for such related elevators.

35 The control mechanisms or machines each include end members 10 and side frames 11 and 12 carried thereby and extending therebetween, these side frames serving as supporting means for switches and trips. The switches and trips in the present drawings carried by the frame 11 are actuated and used as the connected elevator moves upward and those on the frame 12 when the elevator moves downward. 13 is a shaft journaled in bearings 14 which are carried 40 by the end members 10. One end of this shaft projects sufficiently to carry a sprocket wheel 15 which is driven through a sprocket chain 16 from a second sprocket wheel 17 (Fig. 11) secured on the shaft 18 of the hoist drum 19 of the related elevator, the drum and driving mech-

anism being of usual and well known type for this class of mechanism.

Mounted on the shaft 13 is a traveling head 21 which is traversed along the shaft in the direction indicated by the arrow U during the upward trips of the elevator and in the opposite direction indicated by the arrow D during the downward trips. This movement may be accomplished by threading the body of the shaft between the bearings and mounting thereon a nut which is held against rotation. I prefer, however, to make this portion of the shaft of non-circular cross section, a hexagonal section being shown, and to slidably mount on this non-circular section a sleeve 22 having an external thread 23, the threaded sleeve being hereinafter designated as a worm.

The worm has laterally extending hub portions 24 which turn in ends 25 of the head 21, these ends being externally cylindrical and lying within a cylindrical shell 26 which is secured to the ends 25 as by screws 27 (Fig. 3).

A sector of the lower portion of the shell 26, and sectors of the ends 25, are cut away to provide an opening 28 giving access to the underside of the worm. 29 is a rack having teeth 30 conforming to the pitch of the thread of the worm, which rack is in engagement with the thread of the worm in the opening 28, so that turning of the worm will traverse the head along the rack. The worm may be provided with one or more longitudinal openings parallel to the shaft 13 in which are disposed plugs 31, which plugs are urged apart by compression springs 32 and into frictional engagement with the ends 25 of the head, this frictional engagement having a tendency to rotate the head 21 in the same direction that the worm is turned. The amount of this rotation of the head may be limited by the size of the opening 28 and the engagement of the shell 26 at either side of the opening with the rack 29. Preferably, however, arms 33U, 33D extend from the shell 26, and a guide bar 34, extending between the ends 10, is provided, against, and along the opposite sides of which bar the arms 33U and 33D may seat and slide. This bar is flattened in cross section so that its width is much greater than its thickness and these dimensions are so related to the distances between the arms 33U, 33D that when the greater dimension is upright the head may turn a predetermined amount under frictional urging by the worm, but when this greater dimension is turned to a horizontal position the head is locked against rotation.

To allow for and accomplish such turning the cam bar is provided at its opposite ends with journals 35 which turn in suitable bearings in the frame ends and a drum 36 is mounted on the bar adjacent one of these ends.

37 is a cable which passes around the drum and is securely fastened against displacement, as by a screw 38, at the lower side of the drum. The opposite ends 39, 40 of the cable extend laterally and are secured to the plungers or cores 41, 42 respectively, of oppositely disposed solenoids 43, 44, these solenoids being so disposed, and the length of their stroke with relation to the diameter of the drum 36 being such, that when the core 41 of the solenoid 43 is fully retracted by energization of the solenoid 43, as will be later described, the drum will be so turned that the bar 34 will be disposed with its greatest width in a vertical position, giving maximum movement of the arms 33U, 33D, whereas when

the solenoid 44 is energized and the core 42 is retracted (Fig. 7) the bar 34 will be turned with its greatest dimension horizontal, contacting both of the arms 33U and 33D and locking the head 21 against turning in either direction. The bar 34 (Fig. 5) may be provided with a detent 45, urged as by a compression spring 46 into engagement with a notch 47 in the head 10 which will hold the bar, when its greatest width is vertically disposed, against accidental displacement, and a second notch (not shown) at 90 degrees to said first notch, may be provided for similar retention when the greatest width of the bar is horizontal. It will be understood that the solenoids 43, 44 are only energized momentarily and that after retraction of either core energization is discontinued.

Rigidly secured to the shell 26 of the traveling head, on one side is an elongated cam 50U, and similarly secured to the opposite side of the shell is a similarly elongated cam 50D. These cams are so located around the shell that when the arm 33U is swung against the guide bar 34 the cam 50U will be swung upward into actuating position, whereas the opposite cam 50D will be swung well below such position, substantially as shown in Figs. 3 and 6, and with the opposite arm 33D in these views swung against the opposite face of the guide bar 34, the cam 50D will be swung upward into actuating position. Both cams may be moved to and locked in inactive position, as shown in Fig. 7, by turning the guide bar 34 to horizontal position.

The cams 50U, 50D lie along opposite sides of the head 21 and extend in opposite directions therebeyond, the cam 50U extending in the direction of upward movement, and the cam 50D in the direction of downward movement, of the head. The length of the cams are governed by conditions of use, being of greater length for high speed elevators than for low speed elevators as will be further hereinafter set out.

Adjacent the respective rear ends of the cams are studs 51U and 51D on which are respectively journalled rollers 52U and 52D. These rollers, like the cams, are swung into actuating and inactive position according to the direction in which the head is moved, and in the claims are called trips.

Mounted on the side frames 11 and 12 are a plurality of switch units. Each of these units for the up side includes a bracket 53U which may be suitably secured to the under side of the frame member 11, and for the down side a bracket 53D similarly secured to the frame member 12.

54U and 54D are switch carriers which are oscillatably mounted on pins 55 and have clips 56 which serve to secure to the supports and usual type of tilting mercury switches 57U and 57D respectively, which operate the annunciator signals, and hereinafter designated as control switches. 58U and 58D are electro-magnets which are supported by the brackets 53U and 53D respectively, or by the frame members 11 and 12 in immediate proximity to these brackets. These magnets when energized, as through leads 59U, 60U; 59D, 60D in manner to be later described, attract pole pieces 61U, 61D on the switch carriers 54U and 54D respectively, tilting the control switches 57U and 57D to complete circuits through leads 62U, 62D; 63U, 63D respectively, the control switch 57U being shown in position to close its circuit and the control switch 57D with its circuit broken. 64U and 64D are latch levers which are oscillatably mounted on pins 65 carried by the brackets

53U and 53D, these latch levers each having means such as a protruding lug 66 adapted to limit the swing of the related switch carrier when the switches are in open position, and each have a shoulder 67 adapted to engage and hold the related switch carriers of the control switches when they are tilted under magnet action to closed switch position. The opposite ends of the latch levers on the up and down sides respectively extend over the paths of the rollers 52U or 52D, as the case may be, and when such rollers are in actuating position as is the roller 52U, in Fig. 6, any such lever on the up side which is holding a switch in closed position has its end disposed in the path of such roller and will be tripped by passage of the roller.

70U and 70D are a second set of mercury switches which close the hall light circuits and are hereinafter designated as "hall switches." These hall switches are secured as by clips 71 to carriers 72U, 72D respectively, these carriers being oscillatably mounted on pins 73.

74 are stops which limit the swing of the switch carriers in off position of the switches. The carriers have each an upwardly and outwardly extending arm 75U and 75D respectively, which arms carry rollers 76U and 76D, these rollers being respectively in position to be raised by passage of the cams 50U and 50D when such cams are shifted to actuating position, and to thereby tilt their respective switches and complete circuits through leads 77U, 78U, or 77D, 78D, as the case may be.

In a typical installation there is one of the switch units for the up movement, and one unit for the down movement for each of the intermediate floors, but for the top floor and the ground floor there is one complete unit only for each, parts of this unit in each case being installed on the up side and the complementary parts thereof being installed on the down side. Note that in the section shown in Fig. 3 only magnet 58D and control switch 57D with its latch 64D are shown on the down side, and only the hall switch 70U and its carrier 72U and related parts are shown on the up side.

In Fig. 8, #1M, #2M and #3M, diagrammatically show a single-floor switch group of three related machines, the down side of the machines being shown below the up side. The view also shows the circuits in the traveling cables from these three machines to the annunciators of three related elevators, #1E, #2E, #3E. The control mechanisms for the guide bars of the three machines are also shown and are indicated by the numbers #1C, #2C, #3C.

81U and 81D are the up and down hall lights for the #1 elevator, 82U and 82D the lights for the #2 elevator, and 83U and 83D the lights for the #3 elevator. 84U is the up push button, and 84D the down push button through which the floor signals are established in the annunciators of all three elevators, and which also establishes a circuit lead to the hall light switches. 85, 86 and 87 are respectively the annunciators in the three elevators, #1E, #2E and #3E, which annunciators house the signal lights 88U and 88D, for the various floors.

90 is a circuit from a source of electric current; 91 the usual double pole switch, and 92 a transformer such as is ordinarily used in elevator work to cut the voltage down where signal buttons are employed. 93 is the primary lead from the transformer 92 to the junction boxes 94, 95 and 96 of the traveling cables of the three elevators. From

these junction boxes circuit wires 97, 98 and 99 lead through the respective traveling cables to switches 100, 101 and 102 in the three elevators respectively, and through these switches to all of the signal lights 88U and 88D of the three annunciators 85, 86 and 87 respectively. For each floor, leads 103U and 103D for each elevator, return through the respective cables to joint leads 104U and 104D and through these leads respectively to the leads 62U, 62D of the up and down control switches 57U, 57D of one of the three machines, #1M, #2M and #3M, thence through the leads 63U or 63D of this machine, and the series coupled leads 62U, 63U; 62D, 63D of the related control switches of the other machines to return leads 105U and 105D and through a joint lead 106 to the transformer. All three up, and all three down switches are thus respectively connected in series so that all three switches must be closed to complete an up circuit or a down circuit as the case may be.

From the primary lead 93, leads 107U and 107D lead to the push buttons 84U and 84D respectively, and from these buttons leads 108U and 108D extend through the leads 59U, 59D to the magnets 58U and 58D respectively, being connected to these magnets in parallel. Leads 60U, 60D from these magnets in parallel to the return leads 105U and 105D, through the lead 106 complete the circuits.

From the primary lead 93 also a joint lead 110 extends to all the hall lights 81U, 81D; 82U, 82D, and 83U, 83D. From these lights leads 111U, 112U and 113U lead to the hall switches 70U of the #1, #2 and #3 machines respectively, being connected to these switches through the lead 78U. These switches are also connected through the leads 77U to a joint lead 114U and through this lead to the lead 104U, from which the circuit is adapted to be completed through the control switches 57U and the return leads 105U and 106 to the transformer. Similarly the lights 81D, 82D and 83D are connected through individual leads 111D, 112D and 113D to the down set of switches and through these switches and the return lead 105D and joint lead 106 to the transformer.

120 is a lead from one of the circuit wires 90, jointly to leads 121, 122 and 123 which respectively lead through the traveling cable to switches 124, 125 and 126 in the three elevators, #1E, #2E and #3E. From these switches leads 127, 128 and 129 lead to the control solenoids 43, of the three machines #1M, #2M and #3M, and similar leads 130, 131, 132 lead to the solenoids 44 of these machines. 133, 134 and 135 are respectively leads which complete the return circuit from the solenoids 43, 44, of each of the three machines, through a joint lead 136 to the power circuit.

The switches 124, 125 and 126 are respectively adapted each to close the circuit at option to either solenoid of a machine, typically the switch 124 being adapted to close the circuit through the lead 127 to the solenoid 43, or to close the circuit through the lead 130 to the solenoid 44 both of the #1 machine.

In Fig. 9 the return leads from the circuit wires 97, 98 and 99 lead from the top lights 88D. In this view return leads 140, 141 and 142 lead from the top floor lights 88D of the three annunciators 85, 86 and 87 to the junction boxes of the three elevators and thence through a joint lead 143D to the series connected control switches 57D of the three machines for this particular floor,

thence to the joint lead 106 back to the transformers.

From primary lead 93 a second joint lead 144 extends to the three hall lights 81D, 82D and 83D for this floor. From these lights, leads 145, 146 and 147 respectively lead to the hall switches 73U of the three machines for this floor, thence through a joint lead 148 to the lead 143D and through this lead to the series connected control switches 57D for this floor, thence through the return lead 106 to the transformer. A third lead 107D extends from the primary lead 93 to the hall button 84D, thence through the lead 108D to the three magnets 58D, which magnets accomplish the closing of the switches 57D.

In Fig. 10 the return leads 150, 151 and 152 continue the circuit from the bottom floor lights 83D of the three annunciators 85, 86 and 87 to the junction boxes of the three elevators and thence through a joint lead 153 to the series connected control switches 57U of the three machines for this particular floor, thence to the joint lead 106 and back to the transformer.

From primary lead 93 a second joint lead 154 extends to all three hall lights 81U, 82U and 83U for this floor. From these lights leads 155, 156 and 157 respectively lead to the hall switches 70U of the three machines for this floor, thence through a joint lead 158 to the lead 153 and through this lead to the series connected control switches 57U for this floor of the three machines, thence through the return lead 106 to the transformer.

A third lead 107U extends from the primary lead 93 to the hall button 84U, thence through the lead 108U to the three magnets 58U, which magnets accomplish the closing of the series connected control switches 57U and not only complete the annunciator circuits, but also establish the return lead for the hall switches.

In Fig. 11 a circuit is diagrammatically shown adapted to operate hall lights only. In this operation each machine is entirely independent of any other and no hall buttons are employed; these buttons being omitted, the necessity for low voltage ceases and the circuit here shown is at primary voltage. 90 is the incoming power circuit, 91 the master switch and 160 the primary lead to the junction box 161 of the traveling cable of the elevator. 162 is a lead in the traveling cable to a switch 163 in the elevator. 164 is a return lead to the junction box 161, and 165 a lead from such junction box in common to all of the hall lights, 166U for the lower floor, 166D for the upper floor and 167U, 167D for each of the intermediate floors. From the hall light 166U of the lower floor lead 170 extends through the hall switch lead 78D to the hall switch 7CD for the first floor. From this switch the lead 77D extends to a joint return lead 171 for all the down switches, this lead being continued through a lead 172 back to the power circuit. For any of the intermediate floors, as the sixth floor, a lead 168U extends from the hall light 167U through the lead 78U to the switch 70U of the machine for that floor and through the return lead 77U to a joint lead 173 which is connected through the return lead 172 to the power circuit. Likewise from the hall light 167D of this floor a lead 168D extends to the lead 78D and connected to the switch 70D for such floor and through the return lead 77D from this switch to the joint lead 171, and as before, through the lead 172 to the power circuit.

For the upper floor the hall light 166D is con-

nected through lead 174 and lead 78U to the hall switch 70U for this floor. This switch is also connected through the lead 77U to the joint return lead 173 and the lead 172 to the power circuit.

In using the device, as set out in Figs. 1 to 10 inclusive, any car, as the #1 car, which has been out of passenger service is put into service by closing the switch 100 in the elevator and establishing the annunciator circuit. Also the switch 124 of the control circuit is momentarily closed to complete a circuit through the lead 127 to the solenoid 43 of the control (#1C) of the #1 machine, this action energizing the solenoid 43 of such machine and retracting the plunger 41, rotating the drum 36 anti-clockwise, in Fig. 3, and turning the guide bar 34 into upright position as there shown. Thereafter the elevator is operated in usual manner.

Assuming the condition shown in Figs. 8, 9 and 10 in which switch 101 (of car #2) is open and that cars #1 and #3 are in passenger service, as the cars move upward the switches 59U are open until a hall button 84U on some floor is pushed. Such action through the circuit 108U and return circuits 105U and 106 energizes the three magnets 58U for that particular floor of the three machines closing the three control switches 57U. As these switches close, the shoulders 67 of the latches 64U engage the switch carriers 54U and hold the switches in closed position, establishing an uninterrupted lead from the lead 104U to the lead 105U. Circuits are thus completed through primary lead 93, traveling cable leads 97, and 99 and through the up light 88U of the annunciators 85, and 87 for such floor, the circuits being completed through return leads 103U, lead 104U, the series connected switches 57U and leads 105U and 106 to the transformer of the power line.

It will be understood that these actions take place irrespective of the direction in which the elevators are moving or what position the elevator may have relatively to the floor, or floors, on which the signal buttons are pushed.

As an elevator proceeds upward, the traveling head 21 of each elevator moves upward at proportionate speed. Also at the beginning of its upward movement the head is rotated until the arm 33U engages the guide bar 34, in such rotating movement raising both the cam 50U and the roller 52U into actuating position. As the elevator and the head continue their upward movement the cam successively engages the rollers 76U, raising these rollers and tipping the hall switches 70U successively to establish contact between the leads 77U and 78U in these switches, but unless the related switches 57U have been closed the return circuit from such closed hall switch 70U is open between the lead 104U and the lead 105U and the hall light controlled by such switch is not operated. If, however, the up button has been pushed at any floor, and as before described, the three control switches 57U are closed, this return circuit is established and the hall light corresponding to such elevator on that floor is turned on.

It will here be recalled that the cam 50U extends in advance of the head 21 so that, depending on the extent of this advance, the hall light on a floor on which the up light button has been pushed is turned on as the elevator approaches and in advance of its reaching such floor. Where the speed of the elevator is slow, such advance may well be such that the hall light is turned on only one floor in advance of the elevator, but for high speed elevators the length of the cam will

preferably be such that the hall lights are turned on two or even more floors in advance of the elevator. The hall lights so turned on are maintained until either the cam passes from beneath the roller 76U, ordinarily as the elevator leaves the particular floor, or until the roller 52U strikes the extended arm of the latch 64U, releasing the latch carrier 54U and breaking the circuit of the leads 62U, 63U in the control switch 57U. Obviously only the car which is passing that particular floor trips its related control switch 57U, the remaining switches being still held closed by their latches. This however has no effect on the circuit since the opening of any one of the control switches 57U breaks the series circuit through these switches and opens the annunciation circuit and the hall light circuit for such floor. Subsequently as the remaining cars pass that particular floor they in turn trip the remaining switches, but whether they do so or not is immaterial since no circuit can be established until that floor hall button is again pushed by a would-be passenger.

As any elevator approaches the top floor, if the button on such floor has been pushed and the annunciation circuit through the control switches 57U for such floor closed, the cam 50U turns on the hall light on such floor indicating the approach of the car to that floor to receive down passengers. Ordinarily the travel of the head 21 upward is not sufficient to allow the cam 50U to clear the last up roller 76U, nor sufficient to permit the roller 52U to trip the latch arm 64U. The light therefore on the top floor remains on until such time as the elevator starts down. When this occurs the direction of motion of the hoist drum 19 of the particular elevator is reversed, reversing correspondingly the direction of motion of the shaft 13 of the machine and the head 21 is oscillated in opposite direction until engagement of the arm 33D of the head with the guide rod 34 occurs, such oscillation of the head depressing the cam 50U to inoperative position, allowing the roller 76U to drop and the hall light to be cut off. At the same time the cam 50D is raised to operative position, raising the roller 76D for the floor immediately below the top floor and also if the extension is sufficient, for the second floor therebelow also. This shifting action of the head also brings the roller 52D into actuating position and as the head moves downward this roller trips the latch 64D breaking the annunciation circuit. Attention is called to Fig. 9 of the drawings in which it is shown that the top hall light where the circuit has been established by pressing the button on that floor is controlled by the upward movement of the elevator, whereas the circuit established by such button is cancelled by the downward movement of the elevator.

Subsequently the sequence of operations described takes place on downward movement of the elevator, Fig. 10 showing that the reverse of the action described, Fig. 9, takes place at the lower floor when the elevator descends.

The switch 101, in Figs. 8, 9 and 10, is shown open. Also in Fig. 8 the guide bar 34 of control #2C of machine #2 is shown turned in position which renders the actuating rollers and cams (Fig. 7) inoperative. The shift of the control bar 34 to inoperative position has been effected by moving the switch 125 to complete the circuit through lead 128 to solenoid 43, thus retracting plunger 42 of such solenoid. After such solenoid action the switch 125 is opened and is so shown.

Under these conditions elevator #2 may be operated as for freight or other purposes without showing of annunciation lights in such elevator or effect of the elevator on the hall lights. To restore this machine to passenger service, as before described, the switch 101 is closed and the switch 125 closed to establish a circuit through lead 131 to solenoid 44. After energization such solenoid switch being as before restored to open position.

10 In that hook-up of the machine shown in Fig. 11, as the elevator raising drum 19 turns and raises the elevator the head 21 is shifted to bring the arm 33U against the guide bar 34 and raise the cam 50U to operative position. As the elevator and the coordinated head 21 move upward the cam bar 50U successively closes the switches 70U operating the hall lights 167U of floors 2 to 6 and the down hall light 166D of floor 1. During this movement the cam 50D is depressed away from actuating contact with the switches 70D. When the elevator reaches the top floor and starts its downward movement the direction of rotation of the drum 19 and of the shaft 13 is reversed, the head 21 is shifted to bring the arm 33D against the guide bar 34 and raise the cam 50D into actuating position, at the same time dropping the cam 50U to inoperative position and opening the top floor hall light circuit, moving the cam 50D upward into actuating position 30 closes the switch 70D of the sixth floor and turns on the hall light 161D for that floor.

The subsequent downward movement is a repetition of the above described upward movement.

It will be noted that in the specification the members 52U and 52D which trip the switches 57U and 57D have been referred to throughout as "rollers," and in actual practice such rollers are preferably used. It will be understood, however, that any form of member which accomplishes the tripping of the switches may be substituted, and in the claims the inclusive term "trip" or "trips" has therefore been used.

It will be noted also that in the specification the switches 57U and 57D have been referred to as "control switches" since they not only energize the annunciation lights, but also they make or break the return circuit for the hall lights.

In the claims, these control switches have been usually referred to as "annunciation switches."

50 In the machines the head 21 is moved from one end of the shaft or member 13 to the other end thereof, the machine being ordinarily positioned so that the shaft 13 is horizontal. Throughout the specification and claims, however, the movement of the head has been designated as "upward" or "downward" in accordance with the direction in which it moves relatively to the upward movement of the elevator or the downward movement thereof.

In Fig. 11 the lead 160 is shown as extending through a traveling cable to a switch in the elevator, and it is preferred that the installation be thus made. It will be distinctly understood, however, that the lead 160 may be directly connected into the lead 165, preferably through a switch corresponding to the switch 163 located adjacent the elevator on the bottom floor of the building.

I claim:

1. In an elevator signal machine, a frame having end members and parallel side bars, switching units spaced and secured along said side bars, an elongated rotatable member, intermediate and substantially parallel with said side bars, journaled at its opposite ends in said end members,

and adapted for coupling to said elevator for co-ordinated reversal of rotation responsive to reversal of movement of said elevator, a head traversably mounted on said member, said head having secured on each of its laterally opposite sides, a trip and related cam, said cams respectively, each extending substantially parallel with said member in the direction of actuating movement, means traversing said head forward and backward along said member in respective response to opposite rotations of said member, means responsive to said opposite rotations for oppositely oscillating said head and means limiting said oscillation, to establish in operative position the trip and the related cam extending from said head in the then established movement direction, said switching units each comprising a switch biased open, a manually excitable electro-magnet for closing said switch, latching means for retaining said switch in closed position, said latching means including a trip member; and a second switch biased open, and including a closing member, said members extending into adjacency to said head and into respective cooperative relation with the related said head-carried trip and cam shifted into operative position by oscillation of said head.

2. In an elevator signal machine, a frame having end members and parallel side bars, switching units spaced and secured along said side bars, an elongated rotatable member, intermediate and substantially parallel with said side bars, journaled at its opposite ends in said end members, and adapted for coupling to said elevator for co-ordinated reversal of rotation responsive to reversal of movement of said elevator, a head traversably mounted on said member, said head having secured on each of its laterally opposite sides a trip and related cam, said cams extending substantially parallel with said member, respectively in opposite operating directions; means traversing said head forward and backward along said member in respective response to opposite rotations of said member, means responsive to said rotations for oppositely oscillating said head, and means limiting said oscillation, to establish, in operative position, the said trip, and related said cam extending from said head in the direction of movement established by said rotation; said switching units each comprising a switch biased open, a manually excitable electro-magnet for closing said switch, latching means for retaining said switch in closed position, said means including a trip member; a second switch biased open, and including a closing member, said trip member and closing members extending into the respective paths of a said head-carried trip and related said cam for cooperative actuation thereby when said trip and cam are established in operative positions.

3. In an elevator signal machine, a frame having end members and parallel side bars, switching units spaced and secured along said side bars, an elongated rotatable member, intermediate and substantially parallel with said side bars, journaled at its opposite ends in said end members, and adapted for coupling to said elevator for co-ordinated reversal of rotation responsive to reversal of movement of said elevator, a head traversably mounted on said member, said head having secured on each of its laterally opposite sides, a trip and related cam, said cams extending substantially parallel with said member, respectively in opposite directions, from said head, each an operative distance at least as great as

the switch unit spacing in advance of its related said trip, means traversing said head forward and backward along said member in respective response to opposite rotations of said member, means responsive to either said rotation for oscillating said head and means limiting said oscillation, to establish in operative relation the trip and related cam extending from said head in the direction of movement established by said rotation, said switching units each comprising a switch biased open, a manually excitable electro-magnet for closing said switch, latching means for retaining said switch in closed position, said means including a trip member, and a second switch biased open, and including a closing member, said member extending into the path of the related said head-carried trip and cam respectively when said trip and cam are shifted into operative position by oscillation of said head.

4. An elevator signal machine including a plurality of switching units, and actuating means adapted for coupling to and coordination with movements of an elevator, said means including parts adapted to cooperate with said units; each said unit comprising supporting means, a pair of tilting type switches independently and tiltably supported by said means and biased open, one of said switches including a member extending into the path of a said elevator-coordinated part and adapted for actuation by said part to close said switch and hold same closed during passage of said part; the second of said switches including an armature bar, a latch part, a manually controlled electro-magnet secured to said supporting means in operative proximity to said armature bar and adapted on energization to cooperate with said bar to tilt said switch to closed position, and a second latch part carried by said supporting means and adapted to engage said switch latch part when said switch is tilted to closed position, said second latch part actuatable extending into the path of a second said elevator-coordinated part.

5. An elevator signal machine including a plurality of switching units, and actuating means adapted for coupling to and coordination with movements of an elevator, said means including an elongated cam and a trip; each said unit comprising supporting means, a pair of tilting type switches independently and tiltably supported by said means and biased open, a first of said switches including a member extending into the path of said cam and adapted to cooperate with said cam to close said switch and hold same closed during passage of said member; the second of said switches including an armature bar, a latch part, a manually controlled electro-magnet secured to said supporting means in operative proximity to said armature bar and adapted on energization to cooperate with said bar to tilt said switch to closed position, and a complementary latch part carried by said supporting means and adapted to engage said switch latch part when said switch is tilted to said closed position, said complementary latch part having a part actuatable extending into the path of said trip.

6. A device in accordance with claim 5 in which said cam is extended in the direction of actuating movement to engage at least two said switch closing members in advance of action of said switch trip.

7. In a signal operating device for an elevator, oppositely disposed groups of switching units respectively for the control of signals indicating

upward and downward movement, said units being spaced at intervals along substantially parallel lines, means supporting said units, actuating means for said units, means supporting said actuating means for reversible traversing movement along a path parallel to the alinement of said units, and means adapted to couple said actuating means to said elevator for movement responsive to like reversible movement of said elevator; said units each comprising a pair of switches biased open, a manually controllable electro-magnet adapted to close a first of said switches, a latch adapted to hold said switch closed, said latch having a trip member extending toward the path of said actuating means, the second of said switches having a closing member extending toward said path; said actuating means including a pair of latch trips, and a pair of closer-cams, a trip and a cam respectively of said pairs forming an actuator, and means responsive to reversible movement of said actuating means for shifting each said actuator respectively into the path of the complementary group of switching unit members.

8. In a signal operating device for an elevator, oppositely disposed groups of switching units respectively for the control of signals indicating upward and downward elevator movement, said units being spaced at substantially equal intervals along substantially parallel lines, means supporting said units, actuating means for said units, means supporting said actuating means for reversible traversing movement along a path parallel to the alinement of said units, and means adapted to couple said actuating means to said elevator for movement responsive to like reversible movement of said elevator; said units each comprising a pair of switches biased open, a manually controllable electro-magnet adapted to close a first of said switches, a latch adapted to hold said switch closed, said latch having a trip member extending toward the path of said actuating means, the second of said switches having a closing member extending toward said path; said actuating means including a pair of latch trips, and a pair of closer-cams, a trip and a cam respectively of said pairs forming an actuator, and means responsive to reversible movement of said actuating means for shifting each said actuator respectively into the path of the complementary group of switching unit members.

9. A signal operating device in accordance with claim 8 in which each said cam is extended in the direction of its operating movement to engage at least two said switch closing members in advance of action of the related trip.

10. In an elevator signal-operating machine having trip and actuating parts, signal switching units, each comprising a bracket, a manually energizable electro-magnet supported thereby, a pair of tilting type switches, a pair of carriers each respectively for a said switch; said carrier for a first of said switches being pivotally supported off center in said bracket to bias said switch open, and including an armature extending into switch closing proximity to said magnet and a latch part; a latch member pivotally mounted in said bracket, and having an extending trip arm biasing it toward latching engagement with said latch part; said carrier for the second of said switches being pivotally mounted in said bracket off center to bias said second switch open, and having an actuating arm, said trip and actuating arms extending beyond said

75 bracket and operatively into the path of said trip and actuating parts respectively.

11. In an elevator signal-operating machine having trip and actuating parts, signal switching units, each unit comprising a bracket, a manually energizable electro-magnet supported thereby, a pair of tilting type switches, a pair of carriers each respectively for a said switch, said carriers and latch members each being pivotally hinged in said bracket; said carrier for a first of said switches including a latch part and an armature extending into switch closing proximity to said magnet; a latch member having a trip arm; said carrier for the second of said switches having an actuating arm, and means respectively biasing said switches open and said latch member toward engagement with said latch part; said trip and actuating arms extending beyond said bracket and operatively into the path of said trip and actuating parts respectively.

12. In an elevator signal machine, a frame having end members and parallel side bars, switching units spaced and secured along said side bars, an elongated rotatable member intermediate and 25 substantially parallel with said side bars, journaled at its opposite ends in said end members, and adapted for coupling to said elevator for co-ordinated reversal of rotation responsive to reversal of movement of said elevator, a head 30 traversably mounted on said member, said head having secured on each of its laterally opposite sides, a trip and related cam, both normally inoperative, said cams extending substantially parallel with said member, respectively in opposite 35 directions of operative movement, means traversing said head forward and backward along said member in respective response to opposite rotations of said member, means for oscillating said head in response to a said rotation, to bring toward operative positioning, the said cam, then 40 extending from said head in the direction of movement of said head and the related trip, means selectively operable adapted to limit oscillating movement of said head and establish operative positioning of said cam and trip, or at 45 option to prevent oscillation and hold said cam and trip in inoperative position; said switching units each comprising a switch biased open, a manually excitable electro-magnet for closing 50 said switch, latching means for retaining said switch in closed position, said means including a trip member; and a second switch biased open, and including a closing member, said members 55 extending into adjacency to said head and into respective cooperative relation with the related said head-carried trip and cam, when said trip and cam are shifted into operative position by oscillation of said head.

13. In an elevator signal machine, a frame having end members and parallel side bars, switching units spaced and secured along said side bars, an elongated rotatable member intermediate and substantially parallel with said side bars, journaled at its opposite ends in said end members, and adapted for coupling to said elevator for co-ordinated reversal of rotation responsive to reversal of movement of said elevator, a head 65 traversably mounted on said member, said head having secured on each of its laterally opposite sides, a trip and related cam, both normally inoperative, said cams extending substantially parallel with said member, respectively in opposite directions of operative movement to engage at least two said switching units, means

traversing said head forward and backward along said member in respective response to opposite rotations of said member, means for oscillating said head in response to a said rotation, to bring toward operative positioning, the said cam, then extending from said head in the direction of movement of said head and the related trip, means selectively operable adapted to limit oscillating movement of said head and establish operative positioning of said cam and trip, or at option to prevent oscillation and hold said cam and trip in inoperative position; said switching units

each comprising a switch biased open, a manually excitable electro-magnet for closing said switch, latching means for retaining said switch in closed position, said means including a trip member; and a second switch biased open, and including a closing member, said members extending into adjacency to said head and into respective cooperative relation with the related said head-carried trip and cam, when said trip and cam are shifted into operative position by oscillation of said head.

SAMPSON D. FOSTER.
